UNITED STATES PATENT OFFICE

153,996

DESIGN FOR A DISPLAY CONTAINER OR
SIMILAR ARTICLEHerman G. Treiss, Brooklyn, N. Y., assignor to
Robert P. Foose, New York, N. Y.

Application April 16, 1947, Serial No. 138,435

Term of patent 7 years

(Cl. D80—5)

To all whom it may concern:

Be it known that I, Herman G. Treiss, a citizen of the United States, residing in Brooklyn, county of Kings, State of New York, have invented a new, original, and ornamental Design for a Display Container or Similar Article, of which the following is a specification, reference being had to the accompanying drawing, forming a part thereof.

Fig. 1 is a perspective view of a display container or similar article, showing my new design; and

Fig. 2 is a perspective view of the display container or similar article shown in Fig. 1 in open position.

I claim:

The ornamental design for a display container or similar article, substantially as shown.

HERMAN G. TREISS.
